US0D1107909S

(12) **United States Design Patent** (10) Patent No.: **US D1,107,909 S**
(45) Date of Patent: **** Dec. 30, 2025**

(54) **TUBE CONNECTORS FOR MEDICAL PURPOSE**

(71) Applicant: **Innoventa Medica ApS**, Birkerød (DK)

(72) Inventor: **Niels Erik Holm**, Birkerød (DK)

(**) Term: **15 Years**

(21) Appl. No.: **35/521,536**

(22) Filed: **Jun. 7, 2024**

(80) **Hague Agreement Data**

Int. Filing Date: **Jun. 7, 2024**

Int. Reg. No.: **DM/238157**

Int. Reg. Date: **Jun. 7, 2024**

Int. Reg. Pub. Date: **Jul. 5, 2024**

(30) **Foreign Application Priority Data**

Feb. 23, 2024 (EM) 015051563-0001

(51) **LOC (15) Cl.** **24-02**

(52) **U.S. Cl.**

USPC **D24/129**

(57) **CLAIM**

The ornamental design for tube connectors for medical purpose as shown and described.

DESCRIPTION

1. Tube connectors for medical purpose

1.1 : Perspective

1.2 : Front

1.3 : Back

1.4 : Top

1.5 : Left

1.6 : Right

The representations show the ornamental features of a new tube connector for medical purposes. The features shown in broken lines in the drawings depict environmental subject matter only and form no part of the claimed designs. The top and bottom views are a mirror image of each other.

1 Claim, 6 Drawing Sheets
